ABSTRACT OF THE DISCLOSURE

Road barriers and road dividers are rendered more resistant to impact by vehicles, more elastic and permanently non-deformable, and more economically installed and repaired by using the unique prefabricated arrangement disclosed herebelow. Each span or section of the barrier is composed of two road-embedded supports (or of one embedded) and a plurality of intermediate non-embedded supports resting on the pavement. The horizontal beams, made of reinforced and massive concrete are provided with annularly shaped terminals which slide around two adjoining supports. Washer-like doughnuts may be inserted between superimposed beams to obtain a rail effect. The annular extremities and the doughnut separators are movable (pivotable) about the vertical supports to impart the required elastic effect.

The present invention relates to road barriers and road dividers of unique construction; specifically, to road dividers which have pivotable span joints of prefabricated reinforced massive concrete.

The known barriers which are visible along the highways or which are used as dividers between lanes of opposite traffic are generally formed of metal sheets, aesthetically shaped, lined up in a continuous row and supported at given intervals by poles or stakes solidly anchored in the pavement or in the ground.

These barriers are not usually suited to absorb or at least to minimize the impact caused by an accidental contact with a speeding vehicle, because the elements constituting the barrier are rigidly anchored to the supporting stakes and, consequently, are fixed to the ground.

Furthermore, the elements of these barriers, both horizontal and vertical, upon impact with a vehicle, become generally permanently deformed, so as to require the replacement of an entire span or rail, thus increasing the maintenance cost of the highway.

It is one object of the present invention to provide for a novel type of road barrier or divider, which has a greater resistance to impact because of the dynamic transmission of the impact forces through the pivotable individual elements of the barrier;

It is another object of the invention to provide for a novel type of road barrier which has considerably more resilience when subject to vehicular impacts, because each span of the barrier or divider has at least one vertical terminal thereof not connected fixedly with the ground but resting simply on the surface of the pavement or on the ground itself;

It is still another object of the present invention to provide for a resiliently deformable road barrier which is capable of fully absorbing a vehicular impact with a gradual resilience of the horizontal members of the barrier, said resilience being caused by the unique assembly of the horizontal members' terminals about vertical supporting cylindrical members which are not embedded in the ground or road pavement;

It is yet another object of the invention to provide for a road barrier which allows for rapid and easy installation and for economy in maintenance, because of the

2

prefabricated elements of the barrier which are easily transported, assembled and replaced.

The elements which constitute the road barrier or divider of the present invention are made of prefabricated reinforced concrete which has been subjected to a vibrational treatment in order to render the element more massive. In the jargon of the trade, this treatment is also referred to as "getting out the fat," or minimizing voids in the mass. The horizontal elements of the barrier are pivotably inserted on pilasters or stakes, so as to obtain a movable joint thereabout. Since intermediate every two sequentially fixed or embedded supports there is a plurality of non-embedded similar vertical supports, the movement of the pivotable horizontal elements about their terminal supporters allows the absorption of vehicular impacts with a gradual resilient effect. This effect, coupled with the height of the road divider, prevents, as it can be readily seen, the jumping of a vehicle across the divider and into a lane of incoming traffic or, as the case may be, the leaving of the road due to loss of control of the steering mechanism of the vehicle.

The objects and advantages of the present invention will become more apparent from the following detailed description thereof and from the accompanying drawings, in which:

FIGURE 1 is a side view of a series of elements (spans) in the road barrier or divider;

FIGURE 2 shows in cross-section two adjoining spans, taken along the direction A—A of FIGURE 3;

FIGURE 3 is a top view of the barrier of FIGURE 1;

FIGURE 4 shows partially in cross-section an embedded terminal of the barrier; and

FIGURE 5 shows in cross-section a terminal of the barrier along the direction B—B of FIGURE 2.

With reference to the drawings the road barrier or divider of the invention is composed of a plurality of elements or beams 1, 2, prefabricated of reinforced concrete which has been treated vibrationally to impart a substantially void-free structure. At each extremity of said elements 1, 2, there are provided annuli or doughnut-shaped terminals 3, each terminal having an opening 4 therethrough. In correspondence with each annulus 3 there may be provided a notch joint 10, as shown in FIGURES 2 and 5.

The barrier, furthermore, comprises fixed supports or stakes F, which are also made of the same material of construction. These supports F are installed at regular, predetermined intervals along the highway. Each support F is provided with a lower base 5 for anchoring into the ground and with a vertical cylindrical spindle 6 of diameter preferably smaller than the internal diameter of the openings 4 of elements or beams 1, 2.

The barrier also includes additional supports G for location intermediate the supports F and having structural characteristics similar to those of the fixed supports F, with the exception that the base or foot 7 of supports G is not intended to be embedded in the ground, but to simply rest on the surface thereof.

Elements or beams 1, 2 are mounted and assembled on and between the supports F and the intermediate supports G, so that the cylindrical portions 6 and 8, respectively, are passed through the openings 4 of the terminals 3 of elements 1, 2. As a result, elements 1, 2 are horizontally aligned and superimposed on one another to form a barrier or rail of predetermined height.

If so desired, elements 1, 2 may be vertically separated from each other by means of separating discs 9 mounted about spindles 6 and 8, as shown in the drawings.

It can be readily seen that the number of non-embedded vertical supports G may vary between any two fixed supports F; so can the height of the barrier and

the number of interposed discs 9. All of these variants permit a great flexibility of construction without varying the shape, size or fabrication of the various elements of the barrier.

What is claimed is:

1. Road barrier of prefabricated reinforced concrete which comprises a plurality of horizontal elements having annularly shaped extremities; a first plurality of vertical supports having a substantially cylindrical upper portion inserted in apertures in said extremities and a larger lower base portion imbedded in the ground; a second plurality of vertical supports similar to said first plurality of vertical supports but having a shorter base portion resting on the surface of the ground; said upper portions of the supports having a diameter smaller than the inner diameter of said annularly shaped extremities whereby the horizontal elements are hinged connected to the supports and the second said supports may move relatively to the ground on vehicle impact.

2. The road barrier according to claim 1, wherein said horizontal elements are separated vertically from one another by disc separators inserted on said upper portion of said supports.

3. The road barrier according to claim 1, wherein one or more non-embedded vertical supports are positioned intermediate any two adjoining embedded supports.

4. The road barrier according to claim 1, wherein said annularly shaped extremities and said disc separators are provided with at least one notch therein.
